UNITED STATES PATENT OFFICE.

LIBORIUS SENGE, OF CRESCENT SPRINGS, KENTUCKY, ASSIGNOR TO THE GLOBE-WERNICKE COMPANY, OF CINCINNATI, OHIO.

METAL FILING-CABINET.

972,476.

Specification of Letters Patent. Patented Oct. 11, 1910.

Application filed January 8, 1910. Serial No. 537,026.

To all whom it may concern:

Be it known that I, LIBORIUS SENGE, a citizen of the United States, residing at Crescent Springs, in the county of Kenton and State of Kentucky, have invented certain new and useful Improvements in Metal Filing-Cabinets, of which the following is a full, clear, and exact description, reference being had to the accompanying drawing, 10 forming part of this specification.

My invention relates to filing cabinets for the reception of drawer files of any of the various kinds such as letter or index files, and it has for its object the construction of 15 such cabinets from sheet metal in a simple and efficient manner.

The novelty of my invention will be hereinafter more fully set forth and specifically pointed out in the claims.

20 In the accompanying drawing: Figure 1 is a perspective view of a cabinet embodying my invention and containing compartments for four vertical letter file drawers, two of the drawers being in place, a third being 25 partly withdrawn, while the fourth compartment is shown empty. Fig. 2 is a broken perspective detail of one of the shelves. Fig. 3 is a broken vertical sectional elevation of the cabinet looking from the 30 front. Fig. 4 is a broken sectional plan view of Fig. 3.

The same numerals of reference are used to indicate identical parts in all the figures.

In its preferred form of construction the 35 cabinet consists of the side walls 1, which as shown in Fig. 4 have the front edge bent at right angles as at 2, and again at right angles as at 3, thus forming a rectangular channel 4, and having the rear edge turned 40 as at 5 to form a circular channel 6; and a back 7 having both its edges (only one of which is shown in Fig. 4) bent first at right angles as at 8, and then circularly as at 9 and of such a size as will fit snugly within 45 the circular channel 6 of the sides 1. The shelves 10 (shown in perspective in Fig. 2) have their forward edges bent three times at right angles as shown at 11, 12 and 13. This triple angled front edge is cut away 50 at each side edge of the shelf and notch 14 is cut into the shelf at this point thus forming a projection 15 which is of the same size and fits snugly within the rectangular channel 4 of the front edge of the side 1. 55 At two or more points on the side edges of

the shelf 10 notches 16 are cut in pairs and the portion of the edge remaining is turned up as at 17 to form a tongue. The rear edge of the shelf 10 is turned downwardly and forwardly as shown by the dotted lines to 60 form a circular portion 18 extending across the back approximately the same distance as the triple angled front edge.

An inner spacing wall 19 is interposed between each pair of shelves and adjacent to 65 each of the side walls 1. These inner spacing walls 19 have their upper and lower edges turned outwardly as shown at 20 and 21 Fig. 3, the turned out portions 21 being perforated to receive the tongues 17 and 70 with the portions 20 being turned out a distance sufficient to produce a snug fit in the rectangular channel 4 of the side 1.

If desired a suitable shelf guide 22 may be secured to or held in place by the inner wall 75 19 and also if desired a suitable antifriction shelf roller 23 may be secured to the front lower edge of the inner wall 19.

To assemble the cabinet the telescoping circular parts 5 and 9 of the sides and back 80 1 and 7 are brought into engagement with each other and these parts then inverted, after which the top shelf 10, also inverted, is inserted so that the projections 15 engage the rectangular channels 4 of the sides 1 and 85 the shelf 10 is brought to the position it is to occupy permanently. The inner walls 19 are next inserted and brought into engagement with the rectangular channel 4 of the sides 1 and into engagement with the cylindrical part 18 of the shelf 10, after which the next shelf 10 is inserted and engaged as before described, its tongues 17 passing through the apertures in inner walls 19. Proceeding next with the engagement of the next pair 90 of inner walls 19, then the next shelf 10 and so on until all of the shelves and inner walls have been properly inserted and engaged. The last step in the assembling of the cabinet proper is the insertion of spacers 24 between 100 the inwardly and upwardly turned bottom edge 28 of the side 1 and the last inserted shelf 10; and the securing in place of these spacers 24 by any suitable screws 25. After thus having secured all of the parts of the cabinet in place as just described the cabinet is turned over to its correct position and a suitable top 26 is set in place and secured by screws 27.

It will be seen from the above that I have 110

produced a cabinet constructed of the fewest possible parts; each part being made to so interlock with one or more of the other parts as to be practically self-retained in position, and each part lending its strength to the parts adjacent to it to form an exceedingly rigid structure with the minimum weight.

It will also be observed that I have produced a cabinet which is entirely free from rivets, bolt heads or any other projections on the outside, thus facilitating finishing and permitting the cabinets to be arranged side by side with no waste room between any two of them.

It will further be observed that the main parts of the cabinet are assembled and retained in place without the use of a single rivet or bolt and further that the only fastening means employed, other than the interlocking and tongued portions described, are the small screws 25 for retaining the spacers 24 in place, and the screws 27 for retaining the top 26, and even these screws may be dispensed with and the parts last referred to be held in place by interlocking portions similar to those employed in the other parts of the cabinet, and that even the antifriction rollers 28, when the same are employed, may be attached without the use of rivets and in a similar manner.

Having thus fully described my invention I claim:

1. In a cabinet of the character described, the combination of side walls, a rear wall, an integral telescoping connection between the edges of said rear wall and the rear edges of said side walls, shelves maintained in place partly by the front edges of said side walls and partly by inner spacing walls, and inner spacing walls maintained in place partly by said shelves and partly by the front edges of said side walls, substantially as described.

2. In a cabinet of the character described, the combination of side walls, a rear wall, an integral telescoping connection between

the edges of said rear wall and the rear edges of said side walls, shelves maintained in place partly by the front edges of said side walls and partly by inner spacing walls, inner spacing walls maintained in place partly by said shelves and partly by the front edges of said side walls, and a top piece attached to the upper part of the cabinet to improve the appearance of the finished cabinet, substantially as described.

3. In a cabinet of the character described, the combination of side walls, a rear wall, an integral telescoping connection between the edges of said rear wall and the rear edges of said side walls, shelves maintained in place partly by the front edges of said side walls and partly by inner spacing walls, inner spacing walls maintained in place partly by said shelves and partly by the front edges of said side walls, and spacers inserted between the bottom shelf and the bottom of the side walls to raise said bottom shelf from the bottom edges of said side walls, substantially as described.

4. In a cabinet of the character described, the combination of side walls, a rear wall, an integral telescoping connection between the edges of said rear wall and the rear edges of said side walls, shelves maintained in place partly by the front edges of said side walls and partly by inner spacing walls, inner spacing walls maintained in place partly by said shelves and partly by the front edges of said side walls, spacers inserted between the bottom shelf and the bottom of the side walls to raise said bottom shelf from the bottom edge of said side walls, and a top piece attached to the upper part of the cabinet to improve the appearance of the finished cabinet, substantially as described.

LIBORIUS SENGE.
